UNITED STATES PATENT OFFICE.

WILLIAM ALBERT SCHATZ, OF NEW YORK, N. Y., ASSIGNOR TO ROTAX CO., INC., OF NEW YORK, N. Y., A CORPORATION OF NEW YORK.

DESIGN FOR A LIQUID DISPENSER.

Application filed January 20, 1926. Serial No. 16,190. Term of patent 14 years.

To all whom it may concern:

Be it known that I, WILLIAM A. SCHATZ, a citizen of the United States of America, and a resident of the city of New York, Astoria, borough of Queens, in the county of Queens and State of New York, United States of America, have invented a new, original, and ornamental Design for a Liquid Dispenser, of which the following is a specification, reference being had to the accompanying drawing, forming part thereof. The figure is a perspective view of a liquid dispenser showing my new design. I claim: The ornamental design for a liquid dispenser, as shown.

WILLIAM ALBERT SCHATZ.
